UNITED STATES PATENT OFFICE.

MICHAEL H. MALONEY, OF PLYMOUTH, MASSACHUSETTS.

SPINNING-RING MECHANISM.

1,165,012.

Specification of Letters Patent. Patented Dec. 21, 1915.

Application filed November 28, 1910. Serial No. 594,434.

To all whom it may concern:

Be it known that I, MICHAEL H. MALONEY, of Plymouth, in the county of Plymouth and State of Massachusetts, a citizen of the United States, have invented a new and useful Improvement in Spinning-Ring Mechanism, of which the following is a full, clear, and exact description, reference being had to the accompanying drawings, forming a part of this specification in explaining its nature.

My invention relates to an improvement in that type of spinning ring mechanism employing a traveler ring, and pertains essentially to an improved means for retaining the ring.

The object of my invention is to provide a construction in which the traveler ring is elastically held or maintained in a working normal position and from which position the ring may give or yield to displacing impulses against the elastic influence of means of retention acting to resist such movement and which elastic influence acts also to spontaneously return the ring to its normal position when the ring is relieved of the impulses tending to displace it.

My invention can best be seen and understood by reference to the drawings in which—

Figure 1 is a plan of a type of ring mechanism embodying my invention. Fig. 2 is likewise a plan looking at the ring mechanism from the under side thereof. Fig. 3 shows the same in side elevation. Fig. 4 is a cross section. Fig. 5 is a section showing in enlarged detail a portion of the structure shown in Fig. 4. Fig. 6 is a section taken on the line 6—6 of Fig. 5.

Referring to the drawings: 1 represents a base attachable to a ring rail or other fixture of support 2. The base 1 comprises an annular seating plate 3 having a raised in-turned body portion 4 framing the opening in the base and preferably provided with separate inwardly-extending flanges 5. The upper side of the body 4 and flanges 5 present a top bearing surface 6.

7 represents the traveler ring and 8 the traveler. The ring may be and preferably is the ordinary two flanged type of traveler ring. The traveler ring is provided with an extension 9 which forms practically a part of it. This extension is preferably cylindrical in form and is of such diametrical size as will enable it to extend loosely

through the opening in the base into the chamber formed within its body portion 4. The extension may be attached to the traveler ring in any suitable manner, but preferably by turning outwardly the top edge portion of the extension to form a clip 10 which extends around and grips onto the bottom flange of the traveler ring on the outside.

While as above described the diametrical size of the extension is such that it may extend loosely through the opening in the base and accordingly have freedom of movement in a vertical or axial direction, yet its size is preferably such that it may be rather snugly retained against too excessive angular movement or too excessive movement in a lateral direction. In other words, the relationship of the ring extension and base is preferably such that the inside edge portion of the body of the base or rather its separate flanges 5 will form bearings preventing any undue lateral or angular displacement of the extension and traveler ring attached to it and will act also to guide these parts during any movement they may have. It is also to be observed that the bottom flange of the traveler ring and clip 10 secured to it are larger in diameter than the opening in the base and accordingly lap over or by its top bearing surface 6.

Referring now to the means for elastically supporting and retaining the traveler ring: The means employed consists of elastic members or springs 11 preferably made of spring steel. These spring members are preferably also four in number, quadrangularly arranged, and fixed to the base whereby they may extend from their points of fixture into the chamber formed by the body 9 of the base and connect with the extension 9 of the traveler ring for holding it in an operative normal position. The fixing or retention of the springs is such also as will enable them to yield with the extension and traveler ring as these parts yield to the pulls of the yarn upon the traveler during the operation of the device with the effect that the traveler ring will offer a yielding resistance to the varying impulses exerted by a pull of the yarn, tending all the while to maintain an equilibrium of position between the pull of the yarn on the one hand and the stress of the springs on the other, the springs acting also to spontaneously return the ring to its original operative normal position when all displacing influences cease.

The springs 11 may be secured to the base and made to connect with the extension 9 of the ring in any suitable manner. The method shown is the preferred one, however. It will be understood that the base is of a structure permitting of the use of dies in forming it, the base, in other words, being stamped out from metal plate. Now in the formation of the base provision is made for the retention of the springs 11 by raising the metal plate at the points where the springs are to be retained to form spring chambers 12, the upper walls 13 of which chambers extend from the inside edge to the raised body portion of the base outwardly and downwardly to the outer edge of its seating plate. The springs are secured to the under side of each of the walls 13 by clips 14 stamped out of these walls and turned down and in against the outer ends of the respective springs, thereby acting to bind the same hard against the top walls 13 of their respective chambers.

From the points of their retention the springs extend inwardly clear of the walls 13 of their respective chambers, so that the springs may have freedom to bend or move, and connect with the ring extension 9 at points within the body of the base. The springs preferably connect with the ring extension by the ends of the springs projecting through the wall of the extension, openings being formed therein for receiving the ends of the springs by slots 15 formed in the wall of the extension 9. The springs extend slightly into the hollow of the extension and their ends are turned to prevent withdrawal. The springs act to elastically support the ring, the arrangement of the parts being preferably such that the springs will act to normally support or retain the ring and its extension in a position where these parts will be clear of the base; in other words, in a position where the ring may have perfect freedom of movement. The springs are made so light or of such degree of tension that they will easily yield following and permitting of a yielding or vibratory motion of the ring and extension as these parts are impelled by the pulls of the yarn upon the traveler. Any excessive upward movement of the ring and extension tending to an entire displacement of the ring is prevented by lugs 16 on the extension which are formed by incising the extension and turning out the incised portion. These are arranged to bear against the under side of the top edge to the body of the base or flange 5 just prior to the springs being bent to contact with the interior walls 13 of their respective chambers which, as above explained, form a part of the base. The lugs 16 prevent also the springs from being bent beyond their limit of elasticity. The ring and extension are prevented from entering too far into the

base, which may unduly distort or bend the springs, by the bottom flange of the ring and clip 10 attached to it contacting with the top bearing surface 6 of the base.

In the operation of the device the ring will yield to the varying impulses occasioned by the pull of the yarn upon the traveler, which causes the ring to assume, as said before, an equilibrium of position between the varying pulls of the yarn on the one side and the tension of the springs on the other, resisting such movement. During the movement of the ring, whether this movement be in an axial or in an angular direction, the ring is retained and guided by the bearing of the base against the ring extension. Of course the springs at all times during the operation of the device are tending to return the ring to its normal position, which condition of affairs is effected when all displacing impulses upon the ring cease.

Having thus fully described my invention, I claim and desire to secure by Letters Patent of the United States:—

1. In a ring spinning mechanism, the combination with a traveler ring, of means for elastically supporting said ring in an operative position, the same comprising separate spring members projecting inwardly to connect with said traveler ring at separate points, and means for supporting said spring members.

2. In a ring spinning mechanism, the combination with a base having an opening therein, of a traveler ring having an extension projecting through the opening in said base and loosely retained by said base, whereby the ring may have movement relatively thereto, and means for elastically supporting said ring from said base, said means comprising elastic members fixed to said base and extending to connect with the said ring extension at points inside the inclosure of said base.

3. In a ring spinning mechanism, the combination of a base having an opening in it, a cylindrical member loosely contained within the hollow of said base to project upwardly through the opening therein and laterally retained by said base, and a series of spring members inside said base fixedly connecting therewith and elastically supporting said hollow cylindrical member.

4. In a ring spinning mechanism, a base having a raised inturned body portion framing an opening in said base, a traveler ring having an extension projecting inside said base through the opening therein and loosely cooperating with the inturned body portion of said base, forming a bearing for said extension, means for elastically supporting said ring from said base, said means comprising elastic members fixed to said base to extend beneath the inturned body portion thereof and connect with the por-

tion of said ring extended inside said base, means for securing said elastic members to said base, said extension having also lugs coöoperating with said base acting as a stop 5 for limiting the upward displacement of said ring and preventing undue stress upon said elastic members as said ring is drawn away from said base.

5. In a ring spinning mechanism, the 10 combination with a base having an opening in it, of a traveler ring extending in part through the opening in said base into the interior thereof, and spring members secured to said base and projecting inwardly 15 to connect with said traveler ring at separate points inside said base.

6. In a ring spinning mechanism, the

combination with a base having an opening in it, of a traveler ring extending in part through the opening in said base into the 20 interior thereof, and spring members secured to said base and projecting inwardly to connect with said traveler ring at separate points inside said base, and which base is adapted in part also to provide a stop 25 for limiting the upward displacement of said ring and preventing undue stress upon said spring members as said ring is drawn away from said base.
